UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

APPARATUS FOR TREATING HYDROCARBON OILS.

Original application filed November 30, 1917, Serial No. 204,527. Divided and this application filed December 12, 1918. Serial No. 266,398. Renewed June 16, 1923.

To all whom it may concern:

Be it known that I, CARBON P. DUBBS, a citizen of the United States, now residing in the town of Wilmette, county of Cook, 5 and State of Illinois, have invented certain new and useful Improvements in Apparatus for Treating Hydrocarbon Oils, of which the following is a specification.

This invention relates to an apparatus for 10 treating hydrocarbon oils to produce therefrom products having lower boiling points, and is a division of an original application filed by me on Nov. 30, 1917, Serial #204, 527.

15 Among the salient objects of the invention are to provide an improved apparatus in which the heated hydrocarbons are circulated through a heating coil and into and through a coil still, and then passed to a condenser; and during such treatment subjected to a pressure of the generated vapors; to provide an apparatus in which the rate of circulation in the coils of the oil, its temperature and pressure, are readily and accurately controlled; to provide an apparatus which avoids because of circulating the oil through said tubes the danger of the heating tubes being burned out by precipitation of carbon; to provide an apparatus 20 in which such products that are only partly converted to the desired low boiling point are returned and further circulated through the heating tubes; to provide an apparatus where, by means of controlled air cooled condenser, the grade of distillate allowed to pass from the system is controlled and distillate not up to a desired grade is condensed and automatically returned to the distilling coils and redistilled; to provide an apparatus 25 in which heating tubes are maintained in a furnace within well defined temperature ranges, and the oil caused to circulate in each set of heating tubes; to provide in general, an improved apparatus of the character referred to.

In the drawings:

Fig. 1 and Fig. 1^a together show the side elevation of the apparatus partly in section and with other parts broken away.

50 Fig. 1^b is a fragmentary detail view of a liquid level device.

Fig. 2 and Fig. 2^a are a plan view of the construction shown in Figs. 1 and 1^a.

Fig. 3 is a detail view of one of the condenser members.

55

Fig. 4 is a view partly of end elevations and partly section of the heating coils.

Referring to the drawings, A¹ are furnaces in which the heating tubes are positioned. A² is a tunnel through which the 60 fire for heating the furnaces passes. A³ is a flue tunnel. A⁴ is a flue and stack.

B¹ constitute parallel substantially level heating tubes and B² constitute parallel substantially level distilling tubes. B³, B⁴, 65 B⁵ and B⁶ are return T's on the preheating tubes. B⁷, B⁸ and B⁹ are return T's on the distilling tubes. B¹⁴ and B¹⁵ are bands around the tubes for anchoring the particular heating tubes shown. With the exception of the said anchors the tubes extend freely through the furnace walls and can expand independently thereof. B¹⁶ and B¹⁷ 70 are braces for supporting the tubes B¹ and B².

B¹ is a feed line from any source of supply to pump C², and in this line is throttle valve C³. C⁴ is a charging line to preheating tubes B¹, and in this line is throttle valve C⁵. C⁶ and C⁷ are motors for operating the 80 pumps C² and C⁸. C⁸ is a pump which is supplied through line C⁹ branch from line C¹. C¹⁰ is a discharge line connecting this pump with charging line C⁴ and branching off of discharge line C¹⁰ is a branch line C¹¹ 85 which connects with suction line C⁹ and has positioned on it a pressure relief valve or by-pass valve C¹². C¹³ is a meter of any standard make suitable for the work in hand. C¹⁴ is a standard make check valve. C¹⁵ is 90 an automatic liquid level regulating gauge, and the one shown here is that which is furnished by "S-c" Regulator Company of Fostoria, Ohio, and C¹⁵ shown attached to the end of distilling tubes B² operates to 95 open and close the regulator C¹⁶, which regulator is connected with C¹⁵ by a diaphragm C¹⁷, diaphragm C¹⁷ being positioned in the supply line C⁴. It will be understood that any suitable method may be employed for regulating the level in the distilling tubes B². As this regulator is of standard equip- 100

ment and operates on well known principles and the valve operated by a diaphragm is of standard make and well understood, I have not gone into the description of same here, 5 nor do I claim any part of the regulator itself as new.

B^{10} is a fitting connecting adjacent heating tube B^1 to the supply line C^4 . B^{11} is the fitting on the end of the heating tube B^1 through which the oil in same is discharged 10 into line D^1 . This line D^1 is connected to the bottom of the fitting B^{12} which is secured to the distilling tubes B^2 . The oil is discharged out through the bottom of the 15 fitting B^8 by means of line E^1 and through cooling tank E^2 and then to any suitable storage, not shown, and between said storage and cooling tank E^2 is positioned in line E^1 a throttle valve E^3 , to control the rate of 20 flow of the residuum from the line E^1 ; and a similar throttle valve E^4 is positioned in the line E^1 for obtaining samples of residuum from said line E^1 .

F^1 is a centrifugal pump. F^2 is a motor for operating same. F^3 is a suction line to the pump from the distilling tubes B^2 coming out of the bottom of the fitting marked B^{13} . F^4 is discharge line which enters the side of the fitting B^{12} on the end of the tube marked B^2 . F^5 is a carbon trap on the bottom of the suction line as it comes out of the fitting B^{13} . F^6 is also a centrifugal pump. F^7 is a motor for operating same. F^8 is a suction line to the pump from the heating tubes B^1 coming out of the bottom of the fitting marked B^6 . F^9 is a discharge line from the pump which enters the side of the fitting marked B^{10} on the end of the tube B^1 .

40 G^1 , G^2 , G^3 and G^4 are upwardly inclined vapor lines leading off of the distilling tubes B^2 . Lines G^1 and G^4 connect with a manifold G^5 , which manifold connects by pipe G^6 to a fitting B^8 attached to the distilling tubes B^2 . Lines G^2 and G^3 connect to manifold G^7 , which manifold connects by means of pipe G^8 to the top of fitting B^{13} on the end of the distilling tubes B^2 . These vapor lines G^1 , G^2 , G^3 and G^4 are connected at upper end to a common header G^9 and have positioned on them throttle valves G^{10} , G^{11} , G^{12} and G^{13} . Said manifold G^9 is connected to a top manifold G^{14} by means of bent pipes G^{15} to G^{26} ; and to the center of the top manifold G^{14} is connected pipe G^{27} which connects in turn to coils G^{28} contained in water tank G^{29} . From coils G^{28} , the condenser pipe extends through pipe G^{30} into receiving tank H . From pipe G^{30} is a branch pipe G^{31} having a pressure indicating gauge G^{32} , and out of the pipe G^{31} extends pipe G^{33} on end of which is a valve marked G^{34} . This valve and gauge may be situated in the tail house and affords means for there regulating the pressure.

On tank H are glass liquid gauges H^1 and H^2 , pressure relief valve H^3 , draw off valves H^4 , H^5 and H^6 and pressure gauge H^7 . H^6 is for use in case water is to be drawn off before draining the distillate out through valve H^6 . H^4 is a valve for use in an emergency, for example, when one of the other valves are removed for repair or renewal, and if superficial for showing the workings of the apparatus.

75 J^1 , J^2 , J^3 are supports for the receiving tank H . K is a support for the pipes as shown.

L^1 is a standard indicating pyrometer and is connected with different thermo-sticks, 80 which thermo-sticks are positioned in the furnace in which the tubes B^1 and B^2 are positioned. L^2 is a standard temperature recording instrument and connected to a thermo-stick by a cable, and which thermo-stick is positioned inside the manifold G^{14} . L^3 is a standard temperature recording instrument connected to thermo-sticks, which latter are positioned, one in the heating coils to give the temperature of the oils therein, 85 and one positioned in the large distilling coils, to give the temperature therein. L^4 is a standard level indicating gauge, which is connected by tubing to the receiving tank H and shows the depth of the liquid contained in receiving tank H . L^5 is a standard switchboard, which board contains a standard knife switch for breaking or completing the circuit for operating the charging pump C^2 ; also a knife switch for completing or breaking the circuit for controlling the motor C^7 , which operates the circulating pump C^8 , also a knife switch for breaking or completing the electric current 90 for controlling the electric circulating pump F^1 ; also a knife switch for breaking or completing the electric current for the electric lights in the plant, all of which are enclosed in a house built beneath the water cooling tank G^{29} .

100 M^1 is a gas main for supplying the furnaces in which tubes B^1 and B^2 are contained.

N^1 , N^2 , N^3 and N^4 are supports for the extensions O^1 , O^2 which extensions are simply housing over the ends of the preheating tubes B^1 and the distilling tubes B^2 , which housing is to prevent more or less cooling effect that would be caused by leaving them open to the atmosphere and also to prevent subjecting the ends to varying temperatures.

115 Describing now the operation of the process, the material to be treated is to be drawn from any suitable source of supply through line C^1 by and through centrifugal pump C^2 , through line C^4 into heating tubes B^1 . Then through line D^1 to distilling tubes B^2 which distilling tubes may also be called 120 a vaporizing chamber and when these latter heating tubes have been filled to desired 130

level, pump C² is shut down and valve C³ on line C¹ and valve C⁵ on line C⁴ are closed, and normally remain closed during the rest of the run. Heat is supplied to the 5 furnace A¹ and as soon as a desired vapor pressure has been created on the apparatus, then supply pump C⁸ is started in operation and obtains its supply of raw material through line C⁹ and discharges through line 10 C¹⁰ into line C⁴, valve C¹⁶ being opened, and should the level of the liquid in the distilling tubes B² be of the proper height, then the liquid level regulator C¹⁵ will by means of diaphragm C¹⁷, close the valve C¹⁶ on 15 supply line C⁴, and the back pressure thus created on the line C⁴ will force open the pressure relief valve C¹² and by-pass the oil from the discharge side continuously operating pump C⁸ back into the suction line C⁹, 20 and this operation will continue until the level in the distilling tubes B² drops to a sufficient point to permit the valve C¹⁶ to be automatically opened, thus admitting more raw material into the heating tubes B¹ 25 and B².

Pump F¹ is started and continues to operate during the process. This causes the oil to circulate through the distilling tubes B². This is accomplished by drawing the 30 oil through suction F³ and discharging it back into the tubes, through the discharge pipe F⁴.

The residuum formed in the distilling tubes B² is drawn off either intermittently 35 or continuously through line E¹ through cooling coil contained in tank E² and from there to any suitable storage. The quantity of residuum drawn off from this coil is regulated by means of valve E³ positioned in the 40 line E¹, and samples of said residuum may be obtained at any time through cock E⁴ in line E¹. Pump F⁶ is maintained in operation throughout the process, and the oil in heating tubes B¹, is thus made to circulate 45 by drawing off the oil through suction pipe F⁸ and discharges back into these same tubes through the discharge tubes F⁹.

The vapors generated pass up through 50 lines G¹, G², G³ and G⁴ and manifold G⁹ and from there up through pipes G¹⁵ to G²⁸ into manifold G¹⁴. All the vapors that are condensed up to this point are drained back into the distilling tubes B² while the remaining vapors pass up through line G²⁷ through 55 coil G²⁸ immersed in water in tank G²⁹, and from there pass through line G³⁰ into receiving tank H from which they may be drawn off intermittently or continuously 60 through valves H⁴, H⁵ or H⁶.

It will be seen that this method provides a process for automatically and continuously 65 treating petroleum for the production of lower boiling point products and by means of the independent circulation of the liquids in heating tubes B¹ and distilling tubes B²

permits the furnace in which the tubes are positioned being maintained at a considerably higher heat without injurious effect to the oil and in fact up to certain well defined limits, which limits are readily ascertained for any particular oil, it is of great commercial advantage to have the furnaces hotter than the oil contained in tubes positioned in furnace A¹ or oil and vapors contained in tubes B² and both maintained in 75 rapid circulation through these tubes.

The entire system is preferably subjected to a vapor pressure of from 50 to 500 lbs. per square inch, although the pressure will vary with the conditions. The temperature of 80 the oil will preferably vary from 500 to 1000 degrees Fahrenheit, although these limits are in no sense absolute. The pumps are preferably so operated as to cause a rapid circulation in the tubes B¹ and B². 85

Taking gas oil from the mid-continent field of say, 32° to 34° Baumé, and subjecting the same to approximately 600° F. in the heating zone and from 670° to 850° F., 90 in the vapor chamber, at the same time, subjecting it to a pressure of 100 pounds more or less, a yield of approximately 50% of distillate will be obtained therefrom. When redistilled, this distillate will yield approximately 95 50% gasoline or hydrocarbons having a boiling point of 400° F. The heating tubes are of a diameter from 2" to 4" and the vapor chamber is approximately 10" in diameter.

I claim as my invention:

1. In an apparatus for treating hydrocarbons, the combination with a heating coil, of a vaporizing coil of larger diameter than the heating coil and adapted to be heated to a temperature at or above that maintained in the heating coil, a pump and connections to the heating coil for causing a local circulation therein and another pump connection to the vaporizing coil for causing a local circulation in said coil. 100 105 110

2. In an apparatus for treating hydrocarbons, the combination with a heating chamber, of a vaporizing chamber of larger capacity than the heating chamber, a pump connected by inlet and discharge lines to the heating chamber to cause a local circulation of the oil therein and another pump connected to the vaporizing chamber by inlet and discharge lines, causing local circulation of the oil in said vaporizing chamber. 115 120

3. In an apparatus for treating hydrocarbons, the combination with a heating coil, of a vapor chamber of larger diameter than the heating coil mounted in the heating zone and adapted to bring the hydrocarbon vapors to the same or a higher temperature than the temperature of the hydrocarbons in the heating coil, a condenser connected to the vapor chamber, means separately con- 125 130

nected with the heating coil and vapor chamber for producing local circulations in said elements.

4. In an apparatus for treating hydrocarbons, the combination with a heating chamber, of a vapor chamber of larger capacity than the heating chamber mounted in a heating zone and adapted to be heated to a temperature at or above the temperature of the heating chamber, and means connected with both of said chambers whereby local circulations may be maintained in the respective chambers.

5. In an apparatus for treating hydrocarbons, the combination with a heating chamber, of a vapor chamber of larger capacity than the heating chamber mounted in a heating zone and adapted to be heated to a temperature at or above the temperature of the heating chamber, means connected with both of said chambers whereby local circulations may be maintained in the respective chambers, dephlegmating and condensing means connected to the vapor chamber, and means for maintaining a regulated vapor pressure upon the apparatus.

6. In an apparatus of the character described, the combination with a fire box, of a relatively small heating conduit seated in said fire box, a larger distilling conduit, also seated in said fire box, connections to said conduit, means for supplying oil to the first named conduit, means for taking off vapors from second conduit and condensing the same, means for causing a local cyclic circulation of the oil through the larger conduit and means for maintaining a pressure in the oil in both of said conduits and during condensation.

7. In an apparatus of the character described, the combination with a fire box, of a relatively small heating conduit seated in said fire box, a larger distilling conduit, connections to said conduit, means for supplying oil to the first named conduit, means for taking off vapors from the second conduit and condensing the same, means for causing an independent cyclic circulation of the oil through the larger conduit and means for maintaining a pressure on the oil in both conduits during condensation.

8. In an apparatus of the character described, the combination with a fire box, of a relatively small heating conduit seated in said fire box, a larger distilling conduit, connections to said conduit, means for supplying oil in regulated quantities to the initial conduit, means for causing a rapid and independent forced cyclic circulation through the larger conduit, condensing means connected with the larger conduit, and means for maintaining a pressure on the oil in both conduits during condensation.

9. In an apparatus of the character de-

scribed, the combination with a fire box, of a relatively small heating conduit seated in said fire box, a larger distilling conduit connected therewith, means for independently circulating the oil through the larger conduit, means for drawing off the heavier oil from the larger conduit, means for taking off vapors from the larger conduit and condensing the same, means for maintaining a pressure of the generated vapors on the oil in both conduits during condensation.

10. An apparatus of the character described, comprising a heating chamber, of a heating conduit disposed therein, a distilling conduit, connections between said conduits, means for supplying oil to the first mentioned conduit, means for removing vapors from the distilling conduit, means for causing a local cyclic circulation of the oil through the distilling conduit, and means for maintaining a vapor pressure on the oil in said conduits during treatment.

11. An apparatus of the character described, comprising a furnace, means for receiving oil to heat the same disposed within said furnace, a distilling receiver, connections between said oil in the heating means and the distilling receiver, a vapor discharge for the distilling receiver, and means for causing an independent forced cyclic circulation of oil through said distilling receiver.

12. An apparatus of the character described, comprising a furnace, of a heating conduit within said furnace, a distilling conduit, connections between said conduits, means for supplying oil to the first mentioned conduit, means for taking off vapors from the second conduit, a condenser receiving said vapors, means for causing an independent cyclic circulation of oil through the distilling conduit.

13. An apparatus of the character described, comprising a furnace, of a heating conduit within said furnace, a distilling conduit, connections between said conduits, means for supplying oil to the first mentioned conduit, means for taking off vapors from the second conduit, a condenser receiving said vapors, means for causing an independent cyclic circulation of oil through the distilling conduit, and means for returning condensate from the condenser to the distilling conduit.

14. An apparatus of the character described, comprising a fire box, of a heating conduit disposed therein, means for feeding oil to said conduit, a distilling conduit and a connection between the heating and distilling conduits, means for causing a local cyclic circulation of oil through the distilling conduit, means for removing vapors from said conduit, vapor lines for passing said vapors from said conduit to a condens-

er, throttle valves in said vapor lines, and means for maintaining a pressure on the oil undergoing treatment.

15. An apparatus for treating oils, comprising a heating chamber, a heating conduit disposed therein, means for delivering oil to the heating conduit, a distilling conduit, connections between said conduits, means for discharging vapors from the distilling conduit, including a plurality of vapor lines, a header communicating with said lines, condensing tubes communicating with the header, means for discharging vapors from said tubes, means for returning condensate from the vapor lines to the distilling conduit, and means for maintaining a local cyclic circulation of oil through the distilling conduit.
16. An apparatus of the character described, comprising a furnace, an elongated coil disposed within the furnace for receiving an oil stream to heat the same, a distilling receiver, connections between said coil and said distilling receiver, a vapor discharge from said distilling receiver, and means for causing an independent forced cyclic circulation of the oil stream through said coil.

CARBON P. DUBBS.
